UNITED STATES PATENT OFFICE.

WILLIAM P. ALLEN, OF CHICAGO, ILLINOIS.

SYRINGE.

SPECIFICATION forming part of Letters Patent No. 657,328, dated September 4, 1900.

Application filed March 8, 1899. Serial No. 708,231. (No model.)

To all whom it may concern:

Be it known that I, WILLIAM P. ALLEN, of Chicago, in the county of Cook and State of Illinois, have invented a new and useful Improvement in Vaginal Syringes, of which the following is a full, clear, and exact description, reference being had to the accompanying drawings, forming part of this specification.

10 My invention relates to a douche or syringe for cleansing the vagina and parts connected therewith, and particularly to means for holding the syringe securely in place upon the person.

15 The object of my invention is to provide means through which the interior of the vagina and parts connected therewith may be washed and medicated by the substantially-continuous passage of the washing or medicated liquid through the parts.

It consists, primarily, in means for accomplishing this without permitting the leakage of the washing or medicated liquid upon the garments on or around the patient, while 25 leaving the patient free to change position and move about within reasonable limits.

Many vaginal syringes which were intended to be held in position by hand have heretofore been constructed; but it is a physical impossibility for most if not all patients to hold a syringe in place with sufficient pressure to prevent leakage for a sufficient length of time to effect the desired treatment. Other syringes have been designed to be held in place by the pressure of the patient's body upon them; but both of the constructions above referred to have the great disadvantage of compelling the patient to remain constantly in one position throughout the treatment. My invention avoids all these objections and provides mechanical means for holding the syringe in position tight enough to prevent leakage without confining the patient's hands in any way and without limiting other movements of the body within reasonable limits.

My invention also consists in the details of construction of the syringe and the means for holding it in place hereinafter described and claimed.

In the drawings, Figure 1 is a sectional side view, Fig. 2 a side view, Fig. 3 a plan, and

Fig. 4 a bottom view, of my improved syringe. Fig. 5 is a side, and Fig. 6 a perspective, view of the complete apparatus ready for use.

55

In the drawings similar letters represent similar parts throughout the several views.

A is an imperforate conical top of the syringe, shaped substantially as shown.

B is the base of the syringe, adapted to be attached to the top A by the screw-threads a. This base B is preferably made approximately cylindrical and of the mean diameter—i. e., half the larger diameter—of the cone, so as to afford a brace to the cone at 65 about the middle of its inclined sides.

C is a removable tube adapted to fit in a socket b in the top A and socket c in the base B and form a continuous pipe from the inlet D in base B to the series of holes E in 70 the top A. Around the top A are cut the large slotted holes F, leading into the chamber d, between the walls of A and B and the tube C, having the outlet pipe G.

The parts thus far described are preferably 75 made of hard rubber; but they may be made of any suitable material.

It will readily be seen that by unscrewing base B from A at a the tube C may be taken out and all the parts easily cleaned. The top 80 A extends down beyond the walls of B and forms an air-space H H', which helps to cool the portion of the top A which is below the screw-thread a, and makes its temperature lower than the part above, which is in contact with the hot water inside the syringe.

Around the base B is sprung a bar I. For lightness this is made preferably of wire, as shown; but it may be made solid and of any suitable material. This bar extends on each 90 side of the syringe, forming arms, substantially as shown in the drawings; but the length may be varied within reasonable limits without departing from my invention. This bar also has the additional function of resting 95 against the lower edge of the conical top and supporting and stiffening it. The arms formed by the ends of the bar may be made with and a part of some part of the syringe without departing from my invention.

Pivotedly secured to ends K K' of the bar I is a strap J, adapted to pass up over the shoulder of the patient. The upper portion of this strap might be divided so as to pass

over each shoulder, or two straps might be used without departing from my invention. The tension on the strap may be adjusted by means of a buckle L or other suitable means.

- 5 I find that in general an inelastic strap gives the best results, as the body of the patient gives as much spring as is necessary; but an elastic strap may be used, if desired, without departing from my invention.
- 10 The inlet-pipe D of the syringe is connected by a flexible tube M to the bag or other reservoir N containing the hot water or medicated liquid. The discharge-tube G has attached to it a flexible discharge-tube O.
- 15 The flow of liquid through the syringe and the other parts under treatment may be regulated by means of the clamps P and P' on tubes M and O or by suitable valves placed in the tubes themselves.
- 20 In the operation of my improved apparatus valve P is closed and the reservoir N is filled with the hot water or medicated liquid and placed in any convenient location above the patient's head. The top of the syringe is then
- 25 inserted in the vagina and securely fastened there by the strap J, passed over the patient's shoulder. The shape of the top A has been carefully designed, and the shape shown in the drawings has been found the best for the
- 30 purpose of effectually closing the entrance to the vagina. The syringe being mounted on the bar I, the tension on the strap J is a direct vertical tension and the syringe is held in position much more securely and with much less pressure than would be required were
- 35 the bar omitted and the strap passed directly under the syringe. In practice I find that without the bar it is practically impossible to put sufficient tension on the strap to hold
- 40 the syringe as required, while with the bar as shown the result is obtained with a very light pressure and without any inconvenience to the patient. If an additional pressure is desired, the patient may easily obtain it by
- 45 slightly elevating the shoulder over which the strap passes. The end of tube O is placed in a waste-receptacle, and by manipulating the valves P and P' the liquid in receptacle N is passed through tubes M and C and holes E into the vagina, expanding it until all
- 50 folds and creases are filled and cleansed with the liquid. In cases of prolapsus of the womb the pressure of the water is also used to force it back to its normal position. After
- 55 performing these cleansing and medicating

functions the liquid passes through the slots F into the chamber d and out through the waste-pipe O. By raising or lowering the bag N the pressure of the liquid may be regulated as desired to effect the results above 60 referred to. The medicated liquid may also be forced through the syringe by any of the common forms of force-pumps. When the treatment is completed, the flow of liquid is stopped, the strap J unbuckled, and the syringe removed.

From the foregoing description it will be seen that when the syringe is once secured in position by the strap the patient's hands are entirely free and the patient at perfect 70 liberty to lie down, sit up, or stand, and within the limits of the length of tubes M and O to move about the room, as desired.

By using a slightly-different-shaped syringe upon the bar the apparatus can be used 75 for treating the rectum or deep abscesses.

Having thus described my invention, what I claim as new, and desire to secure by Letters Patent, is—

1. In a vaginal syringe, the combination of 80 a conical top having slotted discharge-openings therein opening into the chamber d, an approximately-cylindrical hollow base B, of approximately the mean diameter of the cone, having therein a discharge-opening G, said base being detachably secured to the under side of said conical top so as to form the chamber d, and a detachable tube adapted to conduct liquid through said chamber d into the 85 vagina.

2. In a vaginal syringe, the combination of 90 a conical top having slotted discharge-openings therein opening into the chamber d, an approximately-cylindrical hollow base B, of approximately the mean diameter of the cone, having therein a discharge-opening G, said base being detachably secured to the under side of said conical top so as to form the chamber d, a detachable tube adapted to conduct liquid through said chamber d into the 95 vagina, arms extending forward and backward from said base B in contact with and adapted to support the edges of said conical top and means for securing straps to the ends of said arms.

WILLIAM P. ALLEN.
